FURNACE FOR NEUTRAL HEATING OF METAL WITH NEUTRAL PREHEAT

Frank A. Rusciano, New York, N. Y., assignor to Metallurgical Processes Co., Newark, N. J., a corporation of New Jersey

Application April 9, 1954, Serial No. 422,013

2 Claims. (Cl. 266—5)

This invention relates to a method for producing rapid and efficient heating of metals to an elevated temperature under non-scaling conditions and to a furnace structure by which such method may be practiced.

In a copending application of F. A. Rusciano, Serial No. 422,074, filed April 9, 1954, and entitled Neutral Heating With Controlled Preheat, a continuous furnace is disclosed in which the initial heating, up to a range of temperatures between about 1000° F. and 1500° F., is conducted rapidly in a direct combustion atmosphere having high heating capacity and a composition which, at higher temperatures, or for prolonged heating periods within the stated range, would be highly scaling to metal, the heating up to the final temperature, which may be as high as 2500° F., being conducted in an atmosphere which is non-oxidizing to the metal or even deoxidizing, if desired, to the slight oxidation which may occur in the initial heating. In the method of the above-mentioned application the heating atmosphere employed in the initial heating is produced by the combustion, in a portion of the heating chamber, of a mixture of air and fuel in such proportion as to effect substantially complete combustion of the fuel, and the non-scaling or de-oxidizing atmosphere employed in the final heating is produced by reaction, in another portion of the heating chamber, of an air-fuel mixture having a large excess, of the order of 100%, in the amount of fuel required for complete combustion. The reaction products produced in this latter portion of the furnace heating chamber contain a large amount of potential heat which is made available by secondary combustion of this rich atmosphere gas externally of the work heating chamber but in heat transfer relation thereto. Specifically this secondary burning is carried out in a supplemental heating chamber disposed above the main heating chamber and separated therefrom by a relatively thin arch of good heat conductive material.

The present invention relates to the same general process of heating the metal to a predetermined initial temperature by the heat of reaction produced by the complete combustion of an air-fuel mixture produced directly in the initial heating chamber, and to its final temperature in a non-scaling atmosphere produced in the final heating chamber, but differs from the process of the aforesaid application in that the metal is protected against oxidation during this initial heating by segregating the so-called oxidizing atmosphere by a layer of a neutral atmosphere derived from the atmosphere in which the final heating is carried out. In the instant invention the secondary combustion chamber of the aforesaid application, for utilizing the potential heat contained in the non-scaling atmosphere gases, has been eliminated and these gases are employed, by the addition of supplemental air, to produce the heat required in the initial heat chamber. This greatly increases the operating efficiency of the furnace and reduces the structural cost thereof, these being among the objects of the invention.

2

A further object is to enable the initial heating, effected by the oxidizing combustion, to be carried to higher temperatures.

Another object is to further protect the metal from scaling during the initial heating period.

Further objects are to simplify the internal conduits of the furnace, the external piping and control valve mechanism and the differential pressure control means employed in the aforesaid application.

10 Other objects and advantages will hereinafter appear.

The production of the non-scaling atmosphere employed in the final heat zone for protecting the metal when it is at elevated temperatures is fully described in a copending application of F. A. Rusciano and H. J. Ness, Serial No. 347,716, filed April 9, 1953, and entitled Method and Apparatus for Producing Controlled Furnace Atmospheres. Briefly, this method comprises adjusting the air-fuel ratio supplied to the burners so that the reaction products, when the reactions are carried to completion, will have CO_2/CO and $\text{H}_2\text{O}/\text{H}_2$ ratios of such value that the sum thereof is substantially equal to one. The reactions resulting from such a mixture release only a small percentage of the available B. t. u. of the fuel, of the order of 25%, and therefore provide a low heating rate and a restricted upper temperature limit. These inherent limitations have been overcome in the processes of each of the previously mentioned applications by further combustion of the atmosphere gases out of contact with the work, as for instance, in radiant tubes passing through the heating chamber or in a combustion chamber partitioned from the heating chamber and in heat transfer relation thereto. These expedients have been commercially successful but they involve structural disadvantages, particularly in large continuous furnaces.

35 In accordance with the present invention the indirect heating of the metal by a secondary combustion chamber or radiant tubes is dispensed with and the gases which form the rich non-scaling atmosphere are employed to directly heat the metal by the secondary combustion thereof in a part of the furnace chamber which, for convenience, may be termed the initial heat zone. This secondary combustion is carried to completion, that is, sufficient air is provided to completely convert the CO and H_2 content of the gases to CO_2 and H_2O . Such an atmosphere in contact with the work at elevated temperatures is highly scaling and therefore, in order to prevent such scaling of the work, the combustion is so controlled that the products thereof do not come into contact with the work while it is above the scaling temperature, that is, above about 1000° F. to 1100° F. Above this lower temperature limit and up to surface temperatures of 1800° F. to 2000° F. the metal is protected by a layer or blanket of neutral gas, freely flowing from the hottest to the coolest end of the work. This layer constitutes the combustible fuel for the initial heat chamber and is gradually consumed as it flows through the chamber by supplying a layer of air thereover in such manner as to effect burning at the upper surface of the fuel gas layer and out of contact with the work, the protective effect of the free flowing gas layer being retained over all parts of the work materially above the lower limit of the scaling temperature range. The work is thus subjected to the high heat of this complete combustion while being protected against the scaling effect thereof. Above about 2000° F. the work is passed into the final heat zone where the heating continues up to final temperature, which may be from 2300° F. to 2500° F. in the rich neutral gas atmosphere created therein. In the production of this latter atmosphere supplemental heat, over that produced by combustion of the rich fuel-air mixture, must be supplied since the flame temperature of

such a mixture is below the desired metal heating temperature. This supplemental heat is provided by pre-heating the air employed in the mixture to a high temperature, preferably around 1000° F. This increases the flame temperature of the rich mixture up to approximately that of a completely combusted atmosphere, that is, up to 2800° F. to 3000° F., and thereby imparts to the final heat zone a heating rate commensurable to that obtainable with a completely combusted atmosphere.

The rich neutral atmosphere of the final heat zone is caused to pass into the initial heat zone to form the free flowing blanket therein by regulated draft conditions in the initial heat zone vents, the location of these vents being such as to draw the neutral gas through the path of travel of the work and hence to envelop the work with a relatively thick layer of these neutral gases.

The invention will be more fully understood by reference to the accompanying drawing in which:

Fig. 1 is a central vertical longitudinal section of a furnace embodying the features of the invention;

Figs. 2 and 3 are vertical transverse sections of the furnace taken on the lines 2—2 and 3—3, respectively, of Fig. 1;

Fig. 4 is a curve showing the relative scaling condition prevailing in the initial heat zone in comparison with that normally inherent in a completely combusted atmosphere; and

Fig. 5 is a schematic view showing the door opening and associated control mechanism of the furnace.

Reference will first be made to Figs. 1 to 3 in which a continuous furnace of the gravity or roll-down type is shown. The furnace is composed of refractory brickwork and includes a base 10, forming an inclined floor for the furnace, and the two opposite side walls 11 and 12. An arched roof 13 extends over the discharge end section of the furnace, and with an end wall 14 and the base 10 and side walls 11 and 12, defines the final or high work temperature heating chamber 15. A second arched roof 16 extends over the charging end section of the furnace and with an end wall 17 and the floor and side walls forms the initial heating chamber 18. The end wall 17 is provided with a work charging slot 19 and the opposite end wall 14 has a similar work discharge slot 21, the work W, shown as round bar stock, being conveyed from the charging slot to the discharge end of the furnace by gravity, rolling upon a series of spaced rails 22, set into the floor of the furnace and composed of a material, such as silicon carbide, which is capable of withstanding both the heat and the load. Water cooled conduits may also be employed for this purpose. It is to be understood, however, that the invention is susceptible to use in furnaces of other types employing any convenient work conveying means.

The bars W come to rest at the discharge end of the furnace against a shouldered portion 23 of the rails 22 and are raised over this shoulder for discharge through the slot 21 by pneumatically operated levers 24. The bars W may be conveniently spaced from contact with each other by loose rings, not shown, which are passed over the ends of alternate bars as they are loaded into the furnace. These spacers prevent the hot bars from tending to adhere to each other and thus facilitates their rolling along the sloping rails 22 following removal of a bar from the discharge end. Better circulation of the hot furnace gases about the bars W, and hence a higher heating rate, also results from this spacing.

The charging and discharging slots 19 and 21 are each provided with a door 26 and 27, respectively, adapted to be opened and closed by pneumatic cylinders, as will appear in connection with a description of Fig. 5. Interlocks, later to be described, are provided, whereby neither door can be opened until the other door is closed so as to prevent a straight draft through the furnace chamber which might disrupt the protecting gas blanket formed in the initial heat chamber 18, as hereinafter described.

The high work temperature heat chamber 15 is provided with a series of burners 28 extending through the opposite side walls 11 and 12. These burners are supplied with a very rich mixture of fuel and air, proportioned so as to provide a non-scaling atmosphere in chamber 15. The mixture, as previously indicated, is one which on complete reaction will produce an atmosphere in which the sum of the CO_2/CO and $\text{H}_2\text{O}/\text{H}_2$ ratios is approximately one. The actual CO_2/CO and $\text{H}_2\text{O}/\text{H}_2$ ratios will vary with temperature, the respective values at 2000° F. being about .32 and .68; at 2150° F. about 0.28 and 0.72; at 2300° F. about 0.26 and 0.74; and at 2500° F. about 0.22 and 0.78. The proper air-fuel mixture for obtaining these ratios is largely independent of the operating temperature and controlled primarily by the ratio of molecular carbon to hydrogen in the fuel. Thus a fuel having a C/H_2 molecular ratio of 0.75, such as propane (C_3H_8) will be restricted to approximately 54% of the oxygen required for complete combustion in order to achieve the above CO_2/CO and $\text{H}_2\text{O}/\text{H}_2$ ratios. With higher C/H_2 ratios, larger proportions of air may be employed. Substantially all industrial furnace fuels will have a C/H_2 ratio between 0.5 and 1.5 and in practice will produce the desired CO_2/CO and $\text{H}_2\text{O}/\text{H}_2$ ratios with a deficiency of air from about 45% to 50%, that is, with a fuel excess of from 80% to 100% of that required for complete combustion. Curves showing these relationships are disclosed in the aforesaid application of Rusciano et al.

The burners 28, as shown in cross-section in Fig. 2, each comprises a burner block 29 of high heat resisting refractory, preferably silicon carbide. The block is elongated to provide a long tunnel, sufficient to permit the air-fuel reactions to be substantially completed in the burner block. It is restricted slightly at its outer end 31 in order to increase the pressure within the block and to discharge the reaction products at a higher velocity, and is directed upwardly against the arched roof 13 so that the reaction products projected thereby will scrub vigorously against this refractory surface and thus ensure that these reactions will be carried to the utmost completion before the products thereof come into contact with the work. This manner of firing also causes the arch surface to become highly heated and thus an effective source of radiant heat for the work.

Highly heated air at suitable pressure is supplied to each of the burner blocks through the vertical passageways 32 which communicate with an air conduit 33, one of which extends along each side of the furnace throughout the length of the final heat chamber 15. Gas or other suitable fuel, under a predetermined pressure, is fed to the burner by a nozzle 34, the relative quantity of air and gas being proportioned by suitable valves, to produce the desired non-scaling atmosphere in chamber 15.

The amount of air supplied to the burners 28, as stated, is only about 50% of that required for complete combustion of the fuel, or otherwise stated, the nozzles 34 are supplied with substantially a 100% excess of fuel, and the heat developed from this incomplete combustion

is only about 25% of the total available B. t. u. content of the fuel employed. In order to utilize this remaining heat and to protect the work in the initial heat zone, the atmosphere from chamber 15 is caused to flow freely from this chamber into chamber 18 through the opening 35 under the effect of the draft in a set of flues, such as 36, disposed in spaced relation across the end wall 17, by which the entire furnace gases are exhausted. It will be noted that the forward end of the roof arch 16 is inclined downwardly at 37 towards the charging slot 19 to form a restricted passageway 38 for the gases leaving chamber 18. Thus the draft effect of flues 36 serves to draw the neutral gas from chamber 15 in a straight path from opening 35 to passageway 38, this also being the path of travel of the work W. Further directional effect is given to this gas by the continuation of the top, bot-

tom and side walls of chamber 15 in this same path of travel whereby there is no change of direction of these gases in passing into chamber 18 and hence a minimum of agitation. These gases, in passing over the work adjacent the outlet 35 of chamber 15, will be cooled to a temperature lower than that prevailing in the upper part of chamber 18, as will more fully appear, and thus eliminate thermal circulation of these gases upwardly towards the roof of chamber 18, thereby retaining this free flowing blanket of gas adjacent to the floor of the furnace. It should be noted that the volume of gas delivered by chamber 15 is slightly greater than the total volume of air to be added to chamber 18 to burn it to completion, approximately 50% of the total air required for complete combustion being supplied through burners 28 and 15 the remaining 50% through a series of slots 39 disposed in spaced relation along the side walls of chamber 18 adjacent the arch 16. Only a portion of this air will be entered through the slots at the left end of chamber 18 and hence the neutral gas, as it enters chamber 18, will have a thickness above the floor of more than half of the depth of the chamber and will thus form a relatively thick blanket over the work at this point.

The air for slots 39 is provided by conduits 41 which terminate in enlarged recesses 42 below the level of the slots 39, impinging upon a refractory brick 43 set in the furnace wall. This construction interrupts the directional effect of the conduits 41 and this, together with the large port areas of the entrance slots 39, causes the air to flow slowly into the chamber 18 adjacent the arch roof 16. This air being at a lower temperature than the burning gases immediately therebelow drifts downwardly into contact with the rich gas flowing along the base of the chamber, combustion occurring at the area of contact of the mass of gas and air with the production of an intense heat at the upper surface of the protective blanket. As the free flowing gas mass moves toward the outlet vents 36, it is gradually consumed by means of this stratified burning with some intermixing with the more completely combusted gas so produced. The rate of dissipation and dilution of the protective blanket may be controlled by the spacing of the air inlet slots 39 and the volume of air supplied respectively thereby, and this blanket should not be completely dissipated until it approaches the loading end of the furnace at a point where the work is below its active scaling temperature. The general contour of the protective blanket is indicated by the dotted line 44.

The work parts W entered through charging slot 19 may be substantially at room temperature and as they pass through chamber 18 they will be heated progressively up to the desired top initial temperature which, as stated, may be about 2000° F. The lower limit of the active scaling range may safely be considered to be about 1050° F. If it is assumed that the bars reach this lower temperature at point A in their travel, then the distribution of the air entered by slots 39 may be adjusted so that the protective blanket is completely dissipated at about this point. Points B to E indicate the position in the travel of the work when it will have attained temperatures of about 1400° F., 1700° F., 1850° F., and 2000° F., respectively. At point E where the gases enter chamber 18 they will be completely neutral to the work and will completely envelope it so that no scaling can result from the combustion occurring at the boundary of the gas and air masses. This condition will continue as the free flowing neutral gas stream moves forward until a point is reached, which, by way of example, may be in the neighborhood of point C, representing a work temperature of about 1700° F., where intermingling of the neutral and oxidizing gases may start to occur in contact with the work. From this point forward the ratio of neutral to oxidizing gas in contact with the work will gradually increase. However, at point C the dilution of the gas blanket will be too slight to produce scale, and as the dilution gradually increases towards the charging end

of the furnace, the work due to its gradually lowered temperature continues to resist oxidation.

The relative scaling rate occurring in chamber 18 as compared to that incident to a completely combusted atmosphere will best be understood by reference to the curves of Fig. 4. In this figure curve F indicates in a general way the scaling rate of a completely combusted atmosphere over a range of temperatures between 1000° F. and 2000° F. The spacing of the temperature's abscissa is in relation to the normal rate of surface heating to be expected at each temperature, and the area disposed above and to the left of curve F is a measure of the total scale produced in heating up to any given temperature. Curve G represents the general scaling rate of a combusted mixture containing a 50% excess of fuel and the vertical ordinate or Y axis H represents the zero scaling rate of a neutral combusted mixture containing approximately a 100% excess of fuel. This latter atmosphere is the one employed in chamber 15 and as the protective blanket in chamber 18. If it be assumed that air additions to chamber 18 are so regulated that above 1700° F. there will be no dilution of the protective atmosphere, at 1400° F. a dilution corresponding to a 50% excess of fuel, and at 1050° F. a complete combustion of the neutral atmosphere, the oxidation rate in chamber 18 will generally follow curve G up to 1400° F. and decrease to zero at about 1700° F., as indicated by curve I, the total oxidation obtainable being represented by the shaded area 45 to the left of curve I. While this area indicates that complete absence of oxidation is not obtained, it should be pointed out that the amount of oxidation represented thereby is a relatively small percentage of that produced by a normal completely combusted atmosphere in heating up to 2000° F. It appears only as a mild discoloration too slight to be properly classified as scale, and is readily reduced in the subsequent heating in the neutral atmosphere of chamber 15.

It is to be understood that the curves F, G and I are for comparison purposes only, the exact shape and position thereof being dependent upon the nature and composition of the metal, the heating rate, the flame temperature of the gas, the extent to which combustion is completed before contact with the metal, and other complex variables. The area 45 representing the amount of oxidation obtained in chamber 18 may be varied by the distribution of the air through the slots 39 and, if desired, the protection may be extended further towards the charging end of the furnace, thereby even further reducing oxidation in the initial heat zone. The condition illustrated by curve I, however, represents a substantially complete freedom from oxidation and is readily obtainable without any material reduction in the high heating rate inherent in heating by complete combustion directly in the heating chamber. It should be remembered that only about 25% of the available heat in the fuel was released by the partial combustion in chamber 15 and that the gas introduced into chamber 18 will, therefore, have a B. t. u. content available for release in chamber 18 of the order of 75% of the B. t. u. value of the fuel, the 25% released in chamber 15 being offset in a large degree by the fact that the gases entering chamber 18 will have a temperature of not less than 2000° F. The temperature produced by the secondary combustion in chamber 18 will, therefore, be of the same order as that which would be obtained by combustion of an equivalent amount of cold fuel and air therein. Therefore, the heating rate in chamber 18 will be substantially equal to that obtainable in a normal direct fired furnace of the same size and configuration. Moreover, due to the sloped roof section 37, these hot gases, at a point where combustion has been completed, are brought into intimate contact with the work adjacent to the entrance slot where the work temperature is well below the active scaling range, so as to extract the maximum amount of heat from 70 the gases before they are exhausted through the outlet

vents 36 provided in the end wall 17. The portion of chamber 18 more remote from the slot 38, where the work is at or above scaling temperature, is enlarged so that sufficient combustion space is provided above the neutral gas blanket, the heating being effected largely by radiation while the work is protected from the oxidizing gases by the blanket of neutral gas.

In addition to the vents 36, at the charging end, a second series of vents 46 is provided at the discharge end. Vents 46 are normally closed; however, and chambers 15 and 18 are vented only through the vents 36. Vents 36 and 46 are each provided at their upper open ends with hoods 47 and 48, respectively, the outlet ports of which are normally closed by dampers 49 and 51, respectively. Air inlet nozzles 52 and 53 are also provided for the hoods 47 and 48, respectively, so arranged in relation to the hood outlet ports as to produce a suction or venturi effect when supplied with air through their respective valves 54 and 55.

The combustion products in chamber 18, in their passage in intimate contact with the cold work, as they exit from this chamber will be reduced to a temperature which may be as low as 2000° F. In order to maintain the proper venting of these gases from the furnace, the vents 36 are provided with air injector nozzles 56 for producing a controlled draft in the vents. This air also assists in cooling the gases to a temperature at which they may safely be passed through a metal recuperator 57, the purpose of which is to preheat the air required for the burners 28.

The recuperator 57 comprises a shell having therein a header 58 connected to an incoming air conduit 59, a header 61 connected to a pair of outlet air conduits 62 and a series of tubes 63 connecting the headers 58 and 61. Conduits 62 extend from the recuperator to the inner wall passages 33 leading to burners 28. The vented gases pass from the flue 36 into one end of the shell 57 and are exhausted from the opposite end through ports 64. Hoods 65 are disposed over the ports 64 and are provided with air injector nozzles 66 for augmenting the draft through the furnace. The aggregate amount of air supplied to the draft producing nozzles 56 and 66 will depend upon the draft required to maintain the chamber 15 at a slight positive pressure relative to chamber 18. The division of this air between the two sets of nozzles will be determined by the exact temperature of the gases vented from chamber 18. If materially above the safe operating temperature of the recuperator, a sufficient volume of air will be supplied to nozzles 56 to cool the gases to the desired temperature of about 2000° F. and only enough air will be supplied by nozzles 66 to boost the draft to the desired degree. However, if the exhaust gases are at or below the desired temperature little or no air will be supplied to the nozzles 56 and the draft will be created primarily by increasing the air supply to nozzles 66. Thus, the preheat temperature of the air supplied to the burners 28 may be maintained at its desired level, preferably at a temperature of about 1000° F.

As previously stated, the damper valves 49 at the upper end of vents 36 are normally closed and all of the furnace gases are vented through the heat exchanger 57. All or a portion of these gases may be diverted from the heat exchanger, if desired, by opening of damper 49 and air injector valve 54.

Damper 51 and injector valve 55 associated with the vents 46 at the discharge end of the furnaces are provided for the purpose of relieving the positive pressure of the furnace gas adjacent slot 21, when the door 27 is momentarily opened to discharge work from the furnace, and thereby prevent or reduce burning of the rich atmosphere about the door opening. These vents also serve to prevent an influx of air into chamber 15 at such times.

The control of injector valve 55, damper 51, door 27 and work ejector 24 at the discharge end of the furnace

and the interlock between doors 26 and 27 will now be explained with reference to Fig. 5.

The control mechanism disposed at the charging end of the furnace comprises an electrically operated reversing valve 67 for supplying air under pressure to the pneumatic cylinder 68, the function of which is to open and close the charging door 26 through the chain 69; a signal lamp 71 for indicating when the discharge door 27 is open; and a control switch 72. At the discharge end a similar reversing valve 73 simultaneously controls pneumatic cylinder 74 to operate the work ejecting levers 24 and cylinder 75 to open the discharge door 27 through linkage 76. Damper 51 is connected to the piston of cylinder 75 through resilient linkage 77 so as to open whenever door 27 is opened. A signal lamp 78 and switch 19 are also provided at the discharge end of the furnace. When the operator at the charging end desires to open the door 26 for insertion of a work piece, he depresses switch 72, interrupting the grounded circuit through the upper contacts and completing a battery circuit at the lower contacts. This latter circuit extends in parallel through the winding of the reversing valve 67 to open door 26, and the signal lamp 78, to indicate the open charging door condition at the discharge end of the furnace, the circuit being completed through the upper contacts of switch 79 to ground. Thus, this circuit can only be completed when switch 79 is in its normal door closing position. Switch 79 in its lowered position interrupts the above-mentioned ground and completes a battery circuit (1) in parallel to the reversing valve 73 to supply air to the cylinder 74 to operate ejector 24, and to supply air to cylinder 75 to open door 27 and actuate damper valve 51; (2) to ejector valve 55 to supply air to the nozzle 53 whereby to produce a suction in the exhaust vents 46; and (3) to signal lamp 71 at the charging end of the furnace. This circuit is grounded through the upper contacts of switch 72 and hence can only be completed when switch 72 is in its normal door closing position. This provides an interlock whereby only one door may be open at any time, thereby minimizing interference with the protective atmosphere blanket by the door opening operations.

It is to be understood that the furnace may be provided with the usual temperature controls and with appropriate zoning of the various burners. In this respect, it is contemplated that slots 39 will normally provide only sufficient air to produce complete combustion of the gases entered into chamber 18. However, should the temperature of the work leaving chamber 18 tend to exceed the desired upper limit, 2000° F. in the example given, excess air may be added through the slots 39 to restore the desired temperature condition in this chamber. If the work fails to attain its desired temperature in chamber 18, this will be reflected in chamber 15, as the work passes therein, so that extra heat will be called for in this chamber. The increase in gas thus supplied to chamber 15 will serve as additional fuel for chamber 18 so as to increase the temperature in chamber 18 until the proper heat balance is established. Controls by which these conditions may be attained are well known in the art and, therefore, have not been included herein.

Obviously, the process is subject to many variations without departing from the essential features of the invention and may be carried out in various other types of furnaces. Therefore, I do not desire to be limited to the details of the specific disclosure of this application except as required by the terms of the appended claims.

What I claim is:

1. A furnace for the neutral heating of metal comprising a heating chamber having a hearth, an inlet opening at one end of the chamber adjacent said hearth for the admission of work and an outlet opening at the opposite end of said chamber adjacent said hearth for the removal of work, a plurality of burner means extending into said chamber at spaced points along a portion there-

of adjacent the outlet opening separate air and fuel supply conduits extending into said burner for the production and entrance of primary gaseous products of reaction of a hydrocarbon fuel and air in which there is a large deficiency of air for complete combustion, venting means for said chamber adjacent said inlet opening for the discharge of said products from said chamber, means for directing said vented products into contact with said air supply conduit, draft producing means for said venting means, means, including other draft producing means, for directing said vented products out of contact with said air supply conduit, a plurality of air inlets spaced along a portion of said chamber adjacent said inlet end and located at progressively increasing distances from said venting means for adding supplemental air to said chamber at spaced points along the path of travel of said products toward said venting means, said air inlets being disposed above the path of travel of said reaction products whereby to intermingle with and effect progressive burning of the reaction products as they approach said venting means, and means for supporting work in transit through said chamber in the path of travel of said primary reaction products.

2. A furnace for the neutral heating of metal comprising a heating chamber having an inlet opening and an outlet opening, a hearth extending therethrough from the inlet opening to the outlet opening for the transit of work through the chamber, a stepped roof for said chamber having a low section extending from a medial point toward said outlet end and a relatively higher section extending from said medial point toward said inlet end, whereby to form a final heating zone and an initial heating zone, means for introducing heated combustion products of an air deficient mixture of fuel and air into said

final heating zone, venting means for the chamber disposed adjacent the inlet opening at a level above the hearth approximately on an extension of the roof line of said final heating zone, suction producing means for said venting means whereby said combustion products will be drawn along said hearth without substantial change of direction from said final heat zone through said initial heating zone to said venting means to thereby form a protective blanket over said work, means for progressively adding supplemental air to said chamber in said initial heating zone at a level substantially above said roof line to produce progressive burning of said combustion products at the upper surface of said blanket as they pass to said venting means, a door normally closing said outlet opening, a normally closed vent for said final heating zone disposed adjacent to said door and means for concurrently opening said door and vent.
